United States Patent Office

Des. 190,076

Patented Apr. 11, 1961

190,076

PULL

La Verne E. Clayton, 4000 Auburn St., Rockford, Ill.

Filed Aug. 29, 1960, Ser. No. 61,918

Term of patent 14 years

(Cl. D10—8)

Figure 1 is a front elevational view of a pull showing my new design.

Fig. 2 is a top plan view of the pull.

Fig. 3 is a side view.

Fig. 4 is a perspective view thereof; and

Fig. 5 is an enlarged sectional view taken along the line 5—5 in Fig. 1.

I claim:

The ornamental design for a pull, substantially as shown.
